[57] CLAIM

The ornamental design for a document clip, substantially as shown and described.

DESCRIPTION

FIG. 1 is a perspective view of a document clip showing my new design in an open position;

FIG. 2 is a perspective view thereof in a closed position;

FIG. 3 is a top plan view, the bottom plan view being a mirror image thereof;

FIG. 4 is a left side elevational view, the right side being a mirror image thereof;

FIG. 5 is a rear elevational view thereof; and

FIG. 6 is a front elevational view thereof.
